WIGGLING FISH LURE

George E. Marbourg, Seattle, Wash.

Application August 29, 1949, Serial No. 4,749

Term of patent 14 years

(Cl. D31—4)

To all whom it may concern:

Be it known that George E. Marbourg, a citizen of the United States, residing at Seattle, Washington, has invented a new, original, and ornamental Design for a Wiggling Fish Lure, of which the following is a specification, reference being had to the accompanying drawing, forming a part thereof, in which

Figure 1 is a perspective view of a wiggling fish lure, showing my new design;

Figure 2 is an end view of the lure shown in Figure 1;

Figure 3 is a sectional side view of the lure taken on line 3—3 of Figure 2; and

Figure 4 is an end view of a bead, a part of the lure, taken on line 4—4 of Figure 3.

I claim:

The ornamental design for a wiggling fish lure, as shown.

GEORGE E. MARBOURG.
